Attorney

UNITED STATES PATENT OFFICE.

ALVIN G. SHERMAN, OF DETROIT, MICHIGAN, ASSIGNEE TO DETROIT VAPOR STOVE COMPANY, OF DETROIT, MICHIGAN, A CORPORATION OF MICHIGAN.

BURNER.

1,257,133.

Specification of Letters Patent. Patented Feb. 19, 1918.

Application filed October 10, 1917. Serial No. 195,800.

To all whom it may concern:

Be it known that I, ALVIN G. SHERMAN, a citizen of the United States, residing at Detroit, county of Wayne, State of Michigan, have invented a certain new and useful Improvement in Burners, and declare the following to be a full, clear, and exact description of the same, such as will enable others skilled in the art to which it pertains 10 to make and use the same, reference being had to the accompanying drawings, which form a part of this specification.

This invention relates to heavy hydrocarbon burners, and has for its object a priming arrangement which allows the introduction of a more volatile fluid to the burner for heating it before the heavy hydrocarbon is burned. Priming arrangements for this purpose are not new but the 20 priming arrangement in this connection is both efficient and very cheap to construct and results in a very large manufacturing saving where the production is large.

In the drawings,—

25 Figure 1, is a side elevation.

Fig. 2, is a plan view.

Fig. 3, is a detail in section.

30 *a* is the stove frame which supports the usual grate *b* and a hydrocarbon burner *c*. The fuel is fed to the hydrocarbon burner through a main *d* which is provided with the usual T-like pipe *e* that acts also as a housing for the needle valve *f*. A pipe such as *g* has usually been employed to complete 35 the line from the main to the burner. It has usually been customary to employ a separate priming conduit to take the priming fluid from the priming basin to the stove.

40 I accomplish the same result in a very satisfactory way and do away with the necessity of tapping the burner twice for two separate fuel lines and using two separate fuel lines by inserting a T-union in the line 45 between the fitting *e* and the pipe *g*. However, by simply inserting a T-union and screwing the two pipes into the threads at the ends of the head of the T the results

would not be very good because the fluid would first drop on the threads in the T- 50 union until it overflowed the threads and ran into the pipe *g* where it would accumulate and result in irregular delivery of fuel to the burner.

I avoid this disadvantage by screwing 55 both pipe ends tightly up against each other and then boring a hole through the end of the pipe *g* by inserting a bit into the opening through the upright of the T-union. This serves to give a smooth inner surface 60 within the T-union and avoids the pulsating effect above alluded to.

i designates the priming basin which is screwed to the frame of the stove at *j*, leaving a portion of the priming basin exposed 65 so that the priming fluid may be easily turned into it. The priming basin has a small nozzle or teat *k* soldered in place which may be simply dropped in the opening in the upright portion of the T-union. 70

From the foregoing it is evident that it is very easy to disassemble the priming basin and the rest of the priming arrangement and that the entire device is very cheap to manufacture. 75

What I claim is:

1. The combination of a burner, a valve housing having a valve seat and screw-threaded on one end, a valve located therein and seating on the valve seat of the housing, 80 a pipe screw-threaded on one end, the ends of the pipe and valve housing screw-threaded being adjacent to each other, a T-union into which the two threaded ends of the pipe and valve housing engage, and a priming basin having a depending teat which can be dropped into the opening of the upright 85 of the T-union.

2. The combination of a burner, a valve housing provided with a valve seat screw-threaded on one end, a valve located therein and seating upon the valve seat in the housing, a pipe having a threaded end adapted 90 to act as a continuation of the line through the valve housing, a T-union into the opposed ends of which the two threaded ends 95

of the pipe and the valve housing are screwed so that the latter two abut, the said upright of the T-union being provided with an opening and the said threaded end of the 5 pipe being provided with an opening which registers with the opening of the upright

of the T, and a priming basin provided with a teat adapted to engage in the opening in the upright portion of the T-union.

In testimony whereof, I sign this specification.

ALVIN G. SHERMAN.
